(57) **CLAIM**

The ornamental design for a novel tower heater/fan with angled side panels over an air deflector grid, angled top, angled bottom, as shown and described.

(**) Term: **14 Years**

DESCRIPTION

(21) Appl. No.: **29/267,190**

FIG. 1 is a left front side perspective view of a novel tower heater/fan with angled side panels angled top and angled bottom.

(22) Filed: **Oct. 6, 2006**

FIG. 2 is right front side perspective view of the novel tower heater/fan of FIG. 1.

Related U.S. Application Data

FIG. 3 is a left rear perspective view of the novel tower heater/fan design of FIG. 1.

(62) Division of application No. 29/241,073, filed on Oct. 21, 2005.

FIG. 4 is a right rear perspective view of the novel tower heater/fan design of FIG. 1.

(51) **LOC (8) Cl.** **23-03**

FIG. 5 is a left side view of the novel tower heater/fan design of FIG. 1.

(52) **U.S. Cl.** **D23/335**

FIG. 6 is a right side view of the novel tower heater/fan design of FIG. 1.

(58) **Field of Classification Search** D23/332,

FIG. 7 is a front view of the novel tower heater/fan design of FIG. 1.

D23/314, 335-337, 340-345, 349-350; 392/360, 392/365-369, 373-376; 312/326; 126/110 B, 126/90 A, 92 A

FIG. 8 is a rear view of the novel tower heater/fan design of FIG. 1; and,

See application file for complete search history.

FIG. 9 is top view of the novel tower heater/fan design of FIG. 1.

(56) **References Cited**

The broken lines showing a control panel and buttons, front grid, rear grid and stand in FIGS. 1-9 are for illustrative purposes only and forms no part of the claimed invention for those figures.
